BARREL HOISTING AND DISPLAY RACK

Roy W. Thompson, Seattle, Wash.

Application November 18, 1931
Serial No. 575,839

1 Claim. (Cl. 248—12)

My invention relates to barrel hoisting and display racks and certain objects of the invention are to provide a rack whereby heavy barrels containing food commodities may be readily hoisted and thus placed on display in very compact form and in position whereby the contents of the barrels may be conveniently drawn off into small containers. Further objects are to provide a rack that is adapted to form a back-ground and advertisement for the sale of liquid foods in a market stall or other place by placing proper advertisements on the face of the rack and by placing labels on the exposed ends of the barrels.

With the above and other objects in view which will appear as the description proceeds, the invention consists of the novel construction, adaptation, combination and arrangement of parts hereinafter described and claimed. These objects are accomplished by devices illustrated in the accompanying drawing; wherein: Figure 1 is a view in front elevation of the rack; Fig. 2 is a view in end elevation; Fig. 3 is a view in transverse vertical section taken substantially on a broken line 3—3 of Fig. 1; Fig. 4 is a detail view in perspective of a hoisting cradle; Fig. 5 is a detail view in perspective of the carriage cradle; and Fig. 6 is a fragmentary view, partly in elevation and partly in section, showing the hoisting ratchet and its associated parts.

Referring to the drawing throughout which like reference numerals designate like parts, the rack consists of a plurality of rectangular up-standing frames each comprising front and rear uprights 5 and 6 respectively that are secured in parallel spaced apart relation by top and bottom transverse members 7 and 8. Said frames are placed in parallel and equally spaced apart relation and secured by front and rear top boards 9 and 10 respectively and by a rear bottom board 11 thus completing the framework of the rack and providing equal vertical compartments 12 as clearly shown in Fig. 1 of the drawing.

The hoisting means comprises a shaft 13 that is mounted on the top of the rack and journaled in a bearing 14 at either end thereof. A handle 15 has extended spaced apart plates 16 fixed to its upper end and said plates are revolvably mounted on one end of said shaft. A ratchet wheel 17 is fixed to the same end of said shaft between said plates. A pawl 18 is pivotally mounted between said plates in engageable relation with said ratchet. A depending rod 19 is pivotally connected to said pawl and extends

downwardly and slidably through a guide 20 fixed to the handle 15. A coiled spring 21 has its ends respectively connected to said rod and handle and is under tension whereby the rod is normally held upward and thus causes said pawl 60 to engage the ratchet. By pulling downward on the lower hooked end 22 of said rod the pawl will be disengaged from the ratchet as will be understood.

A short board 23 is secured to the top of the 65 rack framework and projects over the end thereof to the rear of the ratchet 17. A second pawl, which may be termed a safety pawl and as designated by the numeral 24, is pivotally mounted on the projecting end of said board within a 70 shield frame 25. Said second pawl normally engages said ratchet by force of its own weight and a small chain or cable 26 is secured to said pawl and extends over a pulley 27 mounted within the shield frame. By pulling downwardly on said 75 chain it will be obvious that said pawl will be pivotally lifted out of engagement with the ratchet which is most clearly shown in Fig. 6 of the drawing.

The agents for hoisting the barrels comprises 80 a number of hoisting cradles one of which is shown in detail in Fig. 4. Said cradles consist of a pair of side pieces 28 that are secured in spaced apart relation by a pair of barrel supporting pieces 29 that are transversely superimposed upon the ends of the side pieces and secured thereto. Said supporting pieces are provided with arcuate depressions, as at 30, which receive and support a barrel. Eyebolts 31 are secured through the side pieces 28 and the hook 90 ends 32 of sling cables 33 and 34 are caught into said eyebolts when hoisting a barrel.

In hoisting a barrel a hoisting cradle is first placed on top of a truck cradle which is shown in detail in Fig. 5. Said truck cradle comprises 95 a pair of base boards 35 which are held in spaced apart relation by a pair of upstanding side pieces 36 having their ends secured to the ends of the base boards, and castors 37 are provided for the base boards. Said upstanding 100 side pieces are arranged to fit inside of the side pieces 28 of the hoisting cradle and the barrel supporting pieces 29 therefore rest on said upstanding side pieces, and the ends of the side pieces 28 rest on the base boards 35 of the truck 105 cradle thus providing a very strong support for the barrel. The barrel, which is full of a liquid food commodity such as molasses, olive oil, grape juice or the like, is then placed on the hoisting cradle and, by means of the castors 37, is 110

moved into position at the bottom of one of the vertical compartments 12 with its front end facing outwardly. The ends of the cables 33 and 34 are then hooked into the respective eye-bolts and the centers or middle of said cables are caught or looped over hooks 38 that are fixed to the shaft 13.

After catching the middle of the sling cables 33 and 34 over the hooks 38 the handle 15 is moved back and forth thus revolving the shaft 13 and winding up the two sling cables equally. The barrel is thus raised to the desired position, it being understood of course that the hoisting cradle which supports the barrel leaves the truck 15 cradle on the floor and the topmost barrel is hoisted first in each vertical compartment 12. Opposite pairs of holes 39, as shown in Fig. 3, are provided in the uprights 5 and 6. When the barrel has been hoisted to the desired position, 20 iron pins 40 are inserted in the lower ones of said holes and the hoisting cradle is lowered until its side pieces 28 rest on said pins. The sling cables 33 and 34 are then removed and the barrel is now in its established position on display and conveniently disposed for drawing off its liquid contents through its faucets into small receptacles.

The holes 39 are made in pairs for two reasons. Referring to Fig. 3, the first reason is that the rear end of a barrel may be lifted by raising the rear end of its supporting cradle and retaining said cradle in this position by inserting a pin 40 into the upper rear hole. Thus when a barrel becomes nearly empty the last of its contents may be drained off. The second reason is that when the rear end of a barrel is tipped up, as shown in the lower portion of Fig. 3, the next supporting cradle above may be raised from the lower to the upper holes, or from the dotted to 40 the full line position, to make room for lifting the rear end of the barrel below, it being under-

stood that the device is made as compact and low as possible for the reason that the contents of the barrels must be drawn off by the attendant while he is standing on the floor. To lower a barrel the pawls 18 and 24 are alternately released from engagement with the ratchet 17 by manipulating the rod 19 and cable 26 and a barrel must be lowered very slowly owing to its great weight.

It will now be apparent that I have provided a compact rack by means of which a large number of very heavy barrels, each containing a liquid food commodity, may be hoisted with comparative ease and thus placed on display. The contents of each barrel is labeled on the exposed ends thereof and said contents may be readily drawn off into small containers. The device as a whole forms an attractive background or setting for the market stall of the business which I personally originated and which I call "Liquiteria" and wherein the liquid foods are bought in bulk or barrels and sold in small containers. Having thus described my invention, what I claim and desire to secure by Letters Patent of the United States is:

A barrel hoisting and display rack comprising a plurality of upstanding frames secured together to form a number of unobstructed rectangular vertical compartments, a plurality of flat rectangular hoisting cradles horizontally disposed and arranged for vertical movement within the vertical compartments, each cradle adapted to carry a barrel with its major axis disposed horizontally, the upstanding frames having a plurality of oppositely disposed holes therein, pins adapted to fit into said holes for supporting the cradles at variable heights and whereby the rear pins may be shifted upwardly to succeeding holes for supporting the rear ends of the cradles and barrels in a raised position.

ROY W. THOMPSON.
